TILE FLOOR AND WALL COVERING

John E. Ryan, Danbury, Conn., assignor to Reconstruction Finance Corporation, New York, N. Y., a corporation of the United States

Application September 29, 1948, Serial No. 148,864
Term of patent 14 years

(Cl. D18—2)

To all whom it may concern:

Be it known that I, John E. Ryan, a citizen of the United States, residing at Danbury, in the county of Fairfield and State of Connecticut, have invented a new, original, and ornamental Design for a Tile Floor and Wall Covering, of which the following is a specification, reference being had to the accompanying drawing, forming part thereof.

The figure of the drawing is a plan view of a tile floor and wall covering showing my new design, the design being subject to such repetition of the portion shown as may be necessary to cover any given floor or wall area.

I claim:

The ornamental design for a tile floor and wall covering, as shown and described.

JOHN E. RYAN.
